UNITED STATES PATENT OFFICE.

LEWIS B. JEFFCOTT, OF NEW YORK, N. Y.

CONVERTIBLE DAVENPORT AND BED.

1,072,950.

Specification of Letters Patent. Patented Sept. 9, 1913.

Application filed April 17, 1911. Serial No. 621,582.

To all whom it may concern:

Be it known that I, LEWIS B. JEFFCOTT, a citizen of the United States, and a resident of the city of New York, borough of 5 Manhattan, in the county and State of New York, have invented a new and Improved Convertible Davenport and Bed, of which the following is a full, clear, and exact description.

10 The object of the invention is to provide a new and improved convertible davenport and bed, arranged to permit convenient and quick changing from a davenport or a couch to a bed or vice versa, without requiring 15 much physical exertion on the part of the operator, the parts being securely held in either position to prevent accidental changing of the same, and to permit convenient removal of the parts for cleaning or other 20 purposes.

For the purpose mentioned, use is made of a davenport frame having sides, a bed frame having an outer and an inner section, the sections being fulcrumed on the sides 25 of the davenport frame, and a mattress attached at its ends to the free ends of the said bed frame sections to stretch the mattress when the said bed frame sections are in an extended position, and to double up 30 the mattress between the said bed frame sections when the latter are in folded position.

A practical embodiment of the invention is represented in the accompanying drawings forming a part of this specification, in 35 which similar characters of reference indicate corresponding parts in all the views.

Figure 1 is a sectional side elevation of the convertible davenport and bed showing the parts in position for forming a davenport or a couch; Fig. 2 is a similar view of 40 the same showing the parts in position for a bed; Fig. 3 is a plan view of the same; and Fig. 4 is an enlarged cross section of one of the supporting brackets for the outer bed 45 frame section.

The frame A for the davenport or couch is formed of the sides B, rigidly connected with each other at their rear ends by a cross piece B' and by a back C, and on the inner 50 faces of the sides B are removably secured brackets D, by the use of screws E extending through the brackets D into the sides B, the lower ends of the brackets D being provided with notches D' engaging studs E' attached to the inner faces of the sides B. Thus when the screws E are removed the

brackets D can be lifted out of engagement with the studs E' and hence removed from the frame A. On the lower portion of the brackets D are pivoted at F' side arms of the U-shaped bed frame section F, having a cross bar F² connected with a transverse rail F³, to which is secured the inner end of the wire mattress G secured at its outer end to the cross bar H' of a U-shaped outer frame 60 section H, having the ends of its side arms pivoted at H², on the upper portions of the brackets D, as plainly indicated in the drawings. The cross bar F² of the inner bed frame section F engages segmental guideways I secured on the inner faces of the sides B, and the said guideways I are provided at top and bottom with sides I', I² to limit the up and down swinging motion of the inner bed frame section F. The side 65 arms of the inner bed frame section F are connected by coil springs J with the pivotal ends of tension arms J' fulcrumed at J² on the brackets D, and the said tension arms J' are arranged in the path of the arms H³ held on the side arms of the outer bed frame 70 section H, so that when the latter is swung over from an extended position into a folded position (see Fig. 2), then the said arms H³ engage the tension arms J' and thus swing 75 the same downward into the position shown in Fig. 1, whereby the springs J are placed under tension to assist in swinging the inner bed frame section F into an uppermost position when swinging the outer bed frame 80 section H from the folded position, as shown in Fig. 1, into an extended position, as indicated in Fig. 2.

The outer bed frame section H when swung into folded position, as shown in Fig. 95 1, engages supports or seats K secured to the inner faces of the davenport frame A, as plainly indicated in Fig. 4. A retaining lug L is mounted to slide in a casing L' attached to the support K, and in the casing 100 L' is arranged a spring L² for normally holding the pin L in an outermost position to engage the corresponding side bar of the bed frame section H, with a view to hold the said section against accidental upward 105 movement. It is understood that when the outer bed frame section H is swung into folded position, it engages the pin L and presses the same inward against the tension of the spring L², which latter, after the 110 frame section has passed onto its seat or support K, is forced outward to extend onto

the upper portion of the corresponding side bar of the frame section H.

The seat N for the davenport or couch is provided at one end with lugs N' pivoted on arms O' carrying the front board O for the davenport or couch, the said arms O' being fulcrumed at O² on the brackets D. A piece O³ of fabric or other flexible material connects the board O with the front of the seat N, to form with the board O a complete front for the davenport or couch at the time the seat N is seated on the top of the bed frame section H, as indicated in Fig. 1. The free end of the seat N is held on straps 15 P attached to the cross bar H' of the outer bed frame section H to support the seat N underneath the outer bed frame section H at the time the latter is in an extended position, as shown in Fig. 2. Now when the outer bed frame section H is swung inward 20 into a folded position, as previously explained, then the seat N is carried along and the piece O³ finally exerts a pull on the front board O so as to cause the arms O' 25 to swing whereby the several parts finally move into the position shown in Fig. 1, that is, the seat N is seated on the top of the bed frame section H and the arms O' hang downward and likewise the piece O³ so as 30 to form a complete front for the davenport or couch. The seat N is pushed rearwardly so as to extend its rear end under the lower front portion of the back C thus locking the bed frame section H and the seat N. In 35 opening the bed the board O is pressed in by the operator to slide the seat N outward from under the back C and then the bed is unlocked and free to swing into open position. On the cross bar H' of the bed 40 frame section H are pivoted the legs Q to support the bed frame section H in a horizontal position when extended, as indicated in Fig. 2. When the bed frame section H is to be swung into a folded position the 45 legs Q are swung up against the sides of the cross bar H', as indicated in Fig. 1.

It is understood that when the bed frame section H is swung outward from the folded position shown in Fig. 1 into the extended 50 position shown in Fig. 2, then the mattress G is moved into the horizontal position and given the desired tension so as to form a convertible bed. During the upward swinging movement of the bed frame section H, the arms J' exert pressure in an upward direction against the side arms H³ so as to 55 assist the operator, thereby requiring comparatively little physical exertion on the part of the operator when swinging the bed frame section H into the extended position.

Having thus described my invention, I claim as new and desire to secure by Letters Patent:

1. A convertible davenport and bed, comprising a davenport frame having sides, a

bed frame having an outer and an inner section, the sections being fulcrumed on the sides of the davenport frame, a mattress attached at its ends to the free ends of the said bed frame sections to stretch the mattress when the said bed frame sections are in an extended position and to double up the mattress between the said bed frame sections when the latter are in folded position, a seat, a front for the davenport frame and pivoted on the sides thereof, the said seat being pivoted on the said front, and a flexible connection between the other end of the seat and the free end of the outer bed frame section.

2. A convertible davenport and bed, comprising a supporting frame having sides, a bed frame having an outer and an inner section, the sections being fulcrumed on the sides of the supporting frame, a mattress attached at its ends to the free ends of the said bed frame sections to stretch the mattress when the said bed frame sections are in an extended position and to double up the mattress between the said bed frame sections when the latter are in folded position, supporting lugs on the sides of the supporting frame for engagement by the said outer bed frame section, and retaining means on the said lugs for holding the outer bed frame section in position on the lugs.

3. A convertible davenport and bed, comprising a supporting frame having sides, a bed frame having an outer and an inner section, the sections being fulcrumed on the sides of the supporting frame, a mattress attached at its ends to the free ends of the said bed frame sections to stretch the mattress when the said bed frame sections are in an extended position and to double up the mattress between the said bed frame sections when the latter are in folded position, a spring connected at one end with the said innermost bed frame section, and a tension arm mounted to swing on the side of the supporting frame and connected with the other end of the said spring, the said tension arm being in the path of the outermost bed frame section to be actuated by the latter.

4. A convertible davenport and bed, comprising a davenport frame having sides, brackets removably secured to the inner faces of the said sides, a bed frame made in outer and inner sections separately pivoted on the said brackets, a spring mattress connected at its ends with the free ends of the said bed frame sections, supports secured to the inner faces of the sides of the davenport frame for engagement by the outer bed frame section, and means for holding the said outer bed frame section in position on the said supports.

5. A convertible davenport and bed, comprising a davenport frame having sides,

brackets removably secured to the inner faces of the said sides, a bed frame made in outer and inner sections separately pivoted on the said brackets, a spring mattress connected at its ends with the free ends of the said bed frame sections, tension arms pivoted on the said brackets and in the path of the outer bed frame section, and springs connecting the said tension arms with the said inner bed spring section.

6. A convertible davenport and bed, comprising a frame having sides, a bed frame having an outer and an inner section, the sections having side arms fulcrumed on the sides of the frame, a mattress attached at its ends to the free ends of the said bed frame sections to stretch the mattress when the said bed frame sections are in an extended position and to double up the mattress between the said bed frame sections when the latter are in folded position, segmental guideways attached to the sides of the frame and engaged by the free end of the said inner bed frame section, tension arms mounted to swing at the sides of the supporting frame, springs connecting the side arms of the inner bed frame section with the pivotal ends of said tension arms, and arms held on the side arms of the outer bed frame section and adapted to engage and move the said tension arms to place the said springs under tension.

7. A convertible davenport and bed provided with a pivoted bed frame section, a seat having lugs at one end and straps at the other end connected with the free end of the

bed frame section, and a front having a front board provided with pivoted side arms on which the said seat lugs are pivoted.

8. A convertible davenport and bed comprising a davenport frame having sides, brackets secured to the sides of the davenport frame, a bed frame section pivoted on said brackets, a seat having lugs at one end and straps at the other end connected with the free end of the bed frame section, a front having a front board provided with side arms on which the said seat lugs are pivoted, the said side arms being fulcrumed on the said brackets, and a flexible front piece connecting the said front board with the adjacent end of the seat.

9. A convertible davenport and bed, comprising a supporting frame, a bed frame having an outer and an inner section fulcrumed on the said supporting frame, a mattress attached at its ends to the free ends of the said bed frame sections, a seat, a flexible connection between one end of said seat and the outer bed frame section and a front having a front board provided with side arms mounted to swing on the supporting frame, and to which the other end of said seat is pivoted.

In testimony whereof I have signed my name to this specification in the presence of two subscribing witnesses.
